UNITED STATES PATENT OFFICE.

JEHU D. WILLIAMS, OF ASHLAND, KENTUCKY.

DESIGN FOR A HANDLE FOR SHOVELS, FORKS, OR SIMILAR IMPLEMENTS.

SPECIFICATION forming part of Design No. 34,323, dated April 2, 1901.

Application filed March 5, 1901. Serial No. 49,977. Term of patent 14 years.

To all whom it may concern:

Be it known that I, JEHU D. WILLIAMS, a citizen of the United States, residing at Ashland, in the county of Boyd and State of Kentucky, have invented and produced a new and original Design for Handles for Shovels, Forks, or Similar Implements, of which the following is a specification, reference being had to the accompanying drawing, forming part thereof, in which is represented a side or edge view of the handle.

As shown in the drawing, the leading or material feature of my design consists of a handle having one end enlarged or formed with a curved projection *a*, and bent or curved, as at *b*, and extending in a slightly curved line from the bend to the end of the handle. At its opposite end the handle is rounded and bent or curved, as at *c*, while

that portion *d* of the handle between its bent or curved ends is approximately a straight line. The shovel-blade is also represented in the drawing, while a fork is indicated in dotted lines.

Having described my invention, what I claim as new, and desire to secure by Letters Patent, is—

The design for a handle for shovels, forks and similar implements as herein shown and described.

In testimony whereof I have signed my name to this specification in the presence of two subscribing witnesses.

JEHU D. WILLIAMS.

Witnesses:

M. H. HOUSTON,
L. N. DAVIS.
